UNITED STATES PATENT OFFICE.

CHARLES W. COPELAND, OF NEW YORK, N. Y.

IMPROVEMENT IN VALVE-GEAR FOR STEAM-ENGINES.

Specification forming part of Letters Patent No. **222,459**, dated December 9, 1879; application filed October 3, 1879.

To all whom it may concern:

Be it known that I, CHARLES W. COPELAND, of New York, in the county of New York, and State of New York, have invented a new and useful Improvement in Steam-Engines, of which the following is a specification, reference being had to the accompanying drawings.

The said invention relates to the valve-gear in general use on the engines of the steam-boats on the Ohio and Mississippi and other rivers, commonly known as the "lever valve-gear," as applied to the operating of puppet valves in the class of engines referred to.

In these engines, as is well known, the valve-gear is actuated by a cam of peculiar form, the proportions of which determine the point of cutting off and the extent to which the steam is worked expansively, the point of cutting off not being adjustable after having thus been determined by the form and proportions of the cam. From certain practical difficulties and objections such cams are rarely constructed to cut off at a shorter point than one-half stroke, the more common construction being such as to cut off at about five-eighths the stroke of the piston.

The object of my improvement is, that while the general features of this cam and lever valve-gear are retained, to make such additions that the cam or eccentric determining the maximum point of cut-off, other points within the maximum may be determined by the additional adjustable apparatus which I apply, so that the cut-off having at its maximum point—say five-eighths of the stroke of the piston—the point of cut-off may be adjustable to any point within one-half of the stroke of the piston while the engine is in operation, and without in any manner altering or affecting the operation of the cam and lever valve-gear now in common use on the class of engines referred to.

My invention consists in the application of a trip-motion to the steam-valves, by which they will be reseated earlier in the stroke than if reseated by the action of the cam or eccentric only.

The fall of the valve to the seat is regulated by what is known as a "dash-pot," and which is now in common use with other styles of valve-gear. The time of tripping the valve is

determined by the position of an inclined plane or cam, adjustable by the hand of the engineer, which cam acts to break the connection of the actuating mechanism between the cam or eccentric and the valve, thus permitting the valve to be reseated or closed independently of the actuating movement.

To enable others skilled in the arts to which my improvement appertains to make and use my invention, I will proceed to describe its construction and operation by reference to the accompanying drawings, in which—

Figure 1 is a central vertical longitudinal section of a device embodying the elements of the invention. Fig. 2 is a transverse section of same through the lines *x x* of Fig. 1. Fig. 3 is an end view of the invention. Fig. 4 is a top view of same. Fig. 5 shows an engine having my improved valve-gear attached, and Fig. 6 is a top view of same.

The steam-cylinder *A*, with its valves, the side pipes, *B*, the steam-chests *D*, the oscillatory valve-levers *E*, and the wipers or toes *F*, are all of usual construction and of the form commonly used.

The valve-stem *a*, instead of bearing directly upon the lever *E* or upon a cam, as heretofore, rests upon the front portion of a sliding catch or piece, *b*, which is secured so as to be capable of horizontal movement upon the lever *E*, between the journals *d*. The rear portion of the slide *b* is formed with two corresponding slots, *f*, one on each side, in the outer ends of which are mounted the friction-wheels *g*, hereinafter mentioned. The valve-stem *a* is constructed with a vertical slot, *h*, through which the lever *E* passes, and which is supplied with the feather *i*, which rests upon the front edge of the slide *b*, and constitutes the bearing-surface of the stem *a*. In rear of the valve-stem *a* is secured, in any convenient manner, the slide *k*, the lower end of which is forked and provided with cams *m*. When in position the forked ends of the slide *k* pass downward through the slots *f* in close relation to the friction-wheels *g*: The slide *b* is kept in place by the spring *e* when not forced back by the cams *m*; but when thus forced back the sliding piece or catch passes from under the feather *i* of the valve-stem, and allows the valve to drop to its seat. The fall of the valves to their

seats is controlled by the dash-pots F F, which are filled with any suitable fluid for the purpose. When the lever E is raised the catch b passes upward over the forked end of the slide k until the friction-wheels g meet the inclined planes or cams m, which force the said wheel and sliding catch b outward, drawing the catch from under the feather i, and permitting the valves to be reseated.

The inclined planes or cams m may be adjusted at different heights, and thus the point at which the catch b is to withdraw from under the feather i and allow the valves to drop may be controlled at will.

For the purpose of readily changing the point of cut-off, the slide k has cast upon one of its faces a rack, n, in which works a small pinion, p, which pinion is fastened on the small rod or shaft r. On this shaft is also fastened a hand-lever, o, by moving which the pinion is moved in either direction, and the slide k, with its cams m, raised or lowered, and thus determining the point at which the sliding piece b shall be pushed or drawn from under the feather i of the valve-stem and allow the valve to drop; or the slide k may be thrown out of action entirely, and thus permit the steam-valves to be worked in the usual manner, and the time of seating of the valve determined by the actuating cam or eccentric.

To secure the prompt reseating of the valves when the sliding piece or catch b is withdrawn, I apply the spiral spring t around the upper end of the stem, and bearing upon a shoulder on the stem or on a collar or pin to start the valve back to its seat.

For the purpose of adjusting the spring I employ the adjusting-screw u, by working which more or less pressure may be put on the spring to secure its prompt and proper action.

Although in the arrangement shown on the drawings there are two dash-pots shown to each valve, this is not a necessity, as a single dash-pot may be used either at the upper or lower end of the valve-stem, and it will sometimes be more convenient to do so.

When used at the upper end of the valve-stem, the stem can be prolonged through and above the adjusting-screw u and the dash-pot set above the screw; or the dash-pot may be set below the screw and the valve-stem prolonged through the upper end of the dash-pot, and the adjusting-screw located above the dash-pot. On the other hand, if the dash-pot be placed below the valves, the dash-pot is attached to the lower end of the valve-chest and the lower end of the valve-stem prolonged into the dash-pot, the adjusting-screw u, and the springs for returning the valves to their seats being located as shown in the drawings.

Of course many of the parts here described may be omitted, and still have an adjustable and operating cut-off gear. For instance, the racks and pinions, with their shaft for adjusting the slide k, may be omitted and the slide adjusted by hand and fastened; the dash-pots may be omitted and the valves permitted to fall to their seats unresisted or retarded by friction or other means; the adjusting-screws and springs for securing a prompt return of the valves to their seats may be omitted, and other means, such as the application of weights, used for the purpose; or there may be no such means used, the valves to work so freely as to be returned by gravity alone. Further, the slide k may be omitted and the sliding pieces or catches b adjusted by hand and fastened, or the feather be omitted and a roller or some other substitute applied; but with any or all these omissions or substitutions the result will still be an adjustable cut-off arrangement, in combination with the ordinary lever valve-gear, as has been described, and shown in the accompanying drawings.

What I claim as my invention, and desire to secure by Letters Patent, is—

1. In valve-gear for engines in which the lever is actuated by a rocking cam or lever, a sliding catch operated by a sliding cam, which may be adjusted at different relations to the said sliding catch, and thus govern the point at which the said catch shall be withdrawn from beneath a feather connected with the valve-stem, whereby the said stem is allowed to drop and cut off the steam, substantially as set forth.

2. In valve-gear for engines, the combination of the lever E, sliding piece or catch b, spring e, feather i, and slide k, having cams m, substantially as specified.

3. In valve-gear for engines, the combination of the lever E, sliding catch b, spring e, feather i, and slide k, provided with the cams m, rack n, and pinion p, substantially as specified.

4. In combination with the lever E, actuated by a rocking cam or lever, the sliding catch or piece b, having a spring-tension, the valve-stem a, having the spring t and adjusting-screw u, the feather i, the slide k, having cams m, rack n, and pinion p, substantially as set forth.

In testimony that I claim the foregoing improvement in steam-engines, as above described, I have hereunto set my hand this 27th day of September, 1879.

CHAS. W. COPELAND.
